(57) **CLAIM**

The ornamental design for a wall mountable accessory, as shown and described.

DESCRIPTION

In a preferred embodiment, the nature of this product is as a wall mountable accessory in the form of a toilet paper holder.

FIG. 1 is a top, left, front perspective view of a wall mountable toilet paper holder embodying my new design;

FIG. 2 is a front elevational view thereof;

FIG. 3 is a left side elevational view thereof, the right side elevational view being a mirror image of the left side elevational view shown;

FIG. 4 is a top plan view thereof;

FIG. 5 is a bottom plan view thereof; and,

FIG. 6 is a rear elevational view thereof.
